UNITED STATES PATENT OFFICE.

EDMUND F. HOSKIN, OF CHICAGO, ILLINOIS, ASSIGNOR TO WM. A. SPINKS & CO.,
OF CHICAGO, ILLINOIS, A CORPORATION OF ILLINOIS.

BILLIARD TABLE.

Application filed November 8, 1924. Serial No. 748,699.

To all whom it may concern:

Be it known that I, EDMUND F. HOSKIN, a citizen of the United States, residing at Chicago, in the county of Cook and State 5 of Illinois, have invented a new and useful Improvement in Billiard Tables, of which the following is a specification.

This invention relates to improvements in billiard tables and more especially to the 10 method of fastening and supporting the cushion and rail at the edge of a billiard or pool table. It is to be understood that the term billiard table as here used, therefore, includes pool tables, pocket billiard tables, 15 carom tables and all similar tables having a cushion thereon.

As here shown, the invention is embodied in a table having a bed made of molded material such as Portland cement impregnated 20 with any suitable material such as sulphur. It is to be understood, however, that the invention may be used on any kind of table having any kind of bed such as a bed of natural slate as is commonly used on billiard 25 tables.

By the use of my invention it is possible to make a cushion rail supporting structure that is strong and durable and cheap and easy to manufacture. By the use of my 30 invention, also, the cushion rail and rail of the table are held more firmly, strongly and accurately in place. By the use of my invention, also, it is possible to remove quickly and easily the cushion on such a table and 35 replace the same, for repair or shipping purposes or for substituting different kinds of cushions or rails.

By the use of my invention, also, in mounting the cushion, the same is carried by a 40 metal T-iron strip which in turn is mounted on the bed. By means of this construction, in mounting the cushion, metal and slate are fastened together and this, it will be found, gives a more permanent and accurate fit 45 with less liability of warping or bending.

Other features and advantages of my invention will appear more fully as I proceed with my specification.

In that form of device embodying the 50 features of my invention shown in the accompanying drawings, Figure 1 is a frag-

mentary plan view of the top of a pocket billiard table showing a side and a corner pocket, Fig. 2 is a view in side elevation of one of the corner pockets, Fig. 3 is a view 55 in side elevation of one of the side pockets, and Fig. 4 is a vertical sectional view taken through the cushion, rail, and edge of the bed, between the pockets.

As shown in the drawings, 10 indicates 60 the bed of a table here shown, for the purpose of illustration, as made out of some suitable molded material such as Portland cement impregnated with sulphur under heat and in a partial vacuum to give a suitable 65 hard, smooth, solid bed resembling natural slate. This bed is covered with the ordinary billiard cloth 11 which has its edge tacked at 12 to the wooden strip 13 embedded in the outer edge of the bed. 14 indicates suitable levelling screws disclosed and claimed in a co-pending application and forming no part of the present invention.

15 indicates a T-iron having a horizontal plate or base 15^a with the centrally disposed 70 vertical stiffening flange or rib 16. This T-iron is fastened around the edge of the bed by means of the screws 17 threaded into the nuts 18 which preferably are embedded in the bed 10 as the same is formed. The 80 T-iron is so placed that the vertical flange 16 is substantially in registry with the outer surface 19 of the bed 10. When in this position, it will be seen, that substantially half of the bottom plate 15^a projects out beyond 85 the edge of the bed 10. This T-iron surrounds the whole table except where pockets are desired. The construction of the pockets will be explained more fully hereinafter.

Lying on the inside of the vertical flange 90 16 and on top of the bottom plate 15^a is a wooden cushion strip 20 held in place by means of the screws 21 which are threaded into retaining nuts 22 suitably embedded in the strip 20. The inner edge of the strip 95 20 is beveled as shown and carries the rubber cushion strip 23. 24 indicates the cloth which covers the rubber strip 23. This cloth is fastened onto the strip 20 at its edges in any desired manner, such as by the 100 use of the strips 25 and tacks 26.

27 indicates the rail of the table which it

will be noted is supported by means of the screws 28 extending through the flange 16 of the T-iron. The corner between the flange 16 and the bottom plate 15^a on the outside 5 is filled by means of a strip 29 as shown, which is held in place by the screws 30 which extend through the bottom plate 15^a. 31 indicates a blind rail, apron, or side board below the rail 27 extending downwardly 10 some distance in order to conceal the edge of the bed 10 and improve the appearance of the side of the table. At suitable intervals, glued to the lower edge of this board 13 on the inner side are provided a series of blocks 15 32 which add to the strength of the rail by spacing it away from the edge of the bed.

Pockets are provided by the use of pocket irons as shown in Figs. 2 and 3, the former indicating a corner pocket and the latter 20 a side pocket. These irons are indicated respectively by 33 and 34. It will be seen that they are formed to the shape of the pocket desired and provided with projecting lugs 35 at their ends which overlap the 25 bottom plate 15^a outside of the vertical flange or rib 16 and are held in place by means of the bolts 36 and nuts 37.

While I have shown and described certain 30 embodiments of my invention, it is to be understood that it is capable of many modifications. Changes, therefore, in the construction and arrangement may be made without departing from the spirit and scope 35 of the invention as disclosed in the appended claims, in which it is my intention to claim all novelty inherent in my invention as broadly as possible in view of the prior art.

What I claim as new, and desire to secure 40 by Letters Patent, is:

1. In a table of the character described; a T-iron fastened to the bed of the table at its edge with a horizontal base plate and an upwardly projecting flange; a cushion strip carried by said T-iron on the inside 45 of the vertical flange and on top of the base plate; and a rail carried by said T-iron on the outside of the vertical flange.

2. In a table of the character described; a T-iron mounted at the edge of the bed of 50 said table with its base plate projecting out beyond the edge of said bed and having an upwardly projecting flange; a cushion strip carried by said T-iron on the inside of said vertical flange and on top of said base plate; and a rail carried by said T-iron on the outside of said vertical flange.

3. In a table of the character described; a T-iron fastened at the edge of the table 60 with a horizontal bottom plate and an upwardly projecting flange, said strip being interrupted at the location of pockets; a cushion strip carried by said T-iron and lying inside of the flange and on top of the

base plate; and pockets irons at the location 65 of pockets, each of said irons being shaped to conform to the shape of a pocket and provided with supporting lugs at its ends attached to the base plate of said T-iron.

4. In a table of the character described; a T-iron fastened at the edge of the table with a horizontal bottom plate and an upwardly projecting flange, said strip being interrupted at the location of pockets; a cushion strip carried by said T-iron and lying inside of the flange and on top of the base plate; and pocket irons at the location 70 75 of pockets, each of said irons being shaped to conform to the shape of a pocket and provided with supporting lugs at its ends attached to the base plate of said T-iron on the outside of said flange.

5. In a table of the character described; a T-iron attached to the outer edge of the bed of the table and having a horizontal bottom plate with a vertical stiffening flange; and a cushion strip carried by said T-iron lying on top of the base plate and inside of said vertical flange, said cushion strip being attached to said vertical flange. 90

6. In a table of the character described; a T-iron attached to the edge of the bed of 95 said table and having a horizontal base plate and a vertical stiffening flange, said T-iron being attached by means of screws extending through the base plate and into the bed of the table; and a cushion strip lying on the base plate of said T-iron and inside of the vertical flange thereof and attached thereto by screws extending through 100 said vertical flange and into said cushion strip.

7. In a table of the character described; a T-iron attached to the edge of the bed of 105 said table and having a horizontal base plate and a vertical stiffening flange, said T-iron being attached by means of screws extending through the base plate and into the bed of the table; a cushion strip lying on the base plate of said T-iron and inside of the vertical flange thereof and attached thereto by screws extending through 110 said vertical flange and into said cushion strip; and a rail carried by said T-iron on the outside of said vertical flange. 115

8. In a table of the character described; a T-iron attached to the edge of the bed of 120 said table and having a horizontal base plate and a vertical stiffening flange, said T-iron being attached by means of screws extending through the base plate and into the bed of the table; a cushion strip lying on the base plate of said T-iron and inside of the vertical flange thereof and attached thereto by screws extending through 125 said vertical flange and into said cushion strip; and a rail carried by said T-iron on the outside of said vertical flange, and attached

thereto by screws extending through said vertical flange and into said rail.

9. In a table of the character described; a **T**-iron mounted at the edge of the bed of said table and having a horizontal base plate and a vertically projecting stiffening flange, said base plate projecting out beyond

the edge of said bed of said table; and a cushion strip carried by said **T**-iron on the inside of said vertical flange.

Witness my hand and seal this 21 day of October, 1924.

EDMUND F. HOSKIN. [L. S.]
